UNITED STATES PATENT OFFICE.

ISRAEL R. NORTH, OF BALTIMORE, MARYLAND.

COLLAR-BUTTON GUARD FOR SHIRTS.

1,105,295.

Specification of Letters Patent. Patented July 28, 1914.

Application filed April 2, 1914. Serial No. 828,978.

To all whom it may concern:

Be it known that I, ISRAEL R. NORTH, a citizen of the United States, residing at Baltimore, in the State of Maryland, have 5 invented certain new and useful Improvements in Collar-Button Guards for Shirts, of which the following is a specification.

This invention relates to improved means for preventing the base of a collar button 10 worn in neck-bands of shirts from directly contacting with the neck of the wearer.

Heretofore various constructions of collar-button guards for the back and also for the front of shirt neck-bands have been proposed and used, and while some of them are 15 in a degree effective others are open to serious objection either as to the difficulty of making them, or because of some inconvenience to the wearer who has to apply a 20 collar-button to them.

The object of the present invention is to provide an improved formation of button-hole guard at the opening of shirt neck-bands.

25 The drawing illustrates the invention.

Figure 1 shows an open-front shirt with the improved collar-button guard shown at the left-hand side or underlapping edge. Fig. 2 is a view of the inner surface of the 30 neck-band of a shirt in which a part of the improved collar-button guard is broken away to show the base of the button. Fig. 3 shows one end of an-unfinished neck-band. Fig. 4 shows the strip or piece of tape that 35 is to form the button-guard. Fig. 5 shows the end of the neck-band with the strip attached thereto by the button-hole stitches only. Fig. 6 is a top-edge view of the neck-band showing the continuous loop-shaped 40 button-guard and the collar-button in position. Fig. 7 shows one end and the inner surface of the finished neck-band, and the continuous loop-shaped guard free at one end. Fig. 8 is a reversed or outer surface 45 view of the same end of the neck-band shown in Fig. 7.

Referring to the drawing it will be seen the shirt is of the open-front style, one side, *a*, of the front opening is intended to lap 50 over the other side, *b*, therefore the underlapped end, *c*, of the neck-band, *d*, will carry the collar button and be next to and in con-

tact with the neck of the wearer, and the improved collar-button guard, *e*, is formed at this end, *c*. The neck-band, *d*, may have the 55 usual thickness and usual formation from its over-lapped end, *f*, all the way around until reaching the under-lapped end, *c*.

It will be seen by reference to the drawing, that a strip or piece of tape, *e*, is employed to form the said guard; and the first operation is to lay the said strip flat on the inner surface of the neck-band and form the button-hole slit and make the button-hole 60 stitches, *g*, in both the tape and neck-band 65 simultaneously, so that one end of said guard strip will be attached to the neck-band by the button-hole stitches only, as shown in Fig. 5; the other end, *h*, of the guard strip at this stage of the operation 70 is left free and unattached. The second step of the operation is to form a fold, *i*, at the extremity of said free end, and then lay said folded-end, *i*, on top of the opposite end of the strip and run a cross row of stitches, *j*, 75 through both ends of the strip; this forms on the neck-band a continuous loop, *e*, folded to lie flat and forming two ends, one flat side of which loop is attached to the neck-band, *d*, by the button-hole stitches, *g*, and 80 one end of the loop is fastened to the neck-band by the cross-row of stitches, *j*, all other parts of the loop are free and unattached, as seen in Figs. 6 and 7. This construction of 85 button guard in the form of a continuous loop with a button-hole worked through both neck-band and one side of the loop and the greater part of the loop free, makes it convenient for a person to expand or spread 90 the loop and insert a collar button, *k*. The same collar-button closes the open-front of the shirt and also holds both ends of a 95 collar.

Having described my invention what I claim as new and desire to secure by Letters Patent is—

An open-front shirt having a neck-band provided at its overlapped end with a button-hole which opens through the band, and the underlapped end of the neck-band provided on its inner surface with a collar-button guard in the form of a continuous loop folded to lie flat against the neck-band and having a button-hole whose stitches are 100

worked through both the neck-band and one flat side of said loop and which secure the loop to the neck-band, and a row of stitches crosswise of one end of said flat loop and 5 securing said end to the neck-band, and the other end of said flat loop being free and unsecured.

In testimony whereof I affix my signature in presence of two witnesses,

ISRAEL R. NORTH,

Witnesses:

CHAS. B. MANN,
JOHN W. HENES.
